UNITED STATES PATENT OFFICE.

WILLIAM T. HOOFNAGLE, OF BALTIMORE, MARYLAND.

TYPE-WRITING MACHINE.

SPECIFICATION forming part of Letters Patent No. 622,472, dated April 4, 1899.

Application filed October 22, 1897. Serial No. 666,061. (No model.)

To all whom it may concern:

Be it known that I, WILLIAM T. HOOFNAGLE, a citizen of the United States, residing at Baltimore, in the State of Maryland, have invented certain new and useful Improvements in Type-Writing Machines, of which the following is a specification.

The object of this invention is to produce a type-writing machine upon which a plurality of original copies may be produced simultaneously.

My improved machine comprises a paper-carriage having a series of platens and mechanism for moving the platens longitudinally for letter-spacing and rotating them for line-spacing; a corresponding series of sets of type, and means for simultaneously bringing the same type of each set to the printing-point and impressing its character upon the sheets of paper carried by the platens. In the particular embodiment of the mechanism which is described hereinafter the paper-carriage is movable laterally to bring the platens against the selected type upon the type-carriers and the type are arranged in circular rows upon cylinders which are subject to two movements—a vertical movement to select one of the rows of type and a rotary movement to select or bring to the printing-point the particular type desired. The type-wheels are connected to pinions which are operated by a common rack and they are sustained upon a common bar, said rack imparting simultaneous rotary movement to them and said bar imparting simultaneous vertical adjustment.

In the illustration I have used electrical circuits and electro motors or magnets to operate the various parts. It will be understood, however, so far as the broader features of the invention are concerned, that mechanical operating devices may be substituted. It will also be understood that the type-wheels may be moved to the platens instead of the reverse, that being a common mode of operating type-wheels.

For a detailed description of the invention reference is had to the accompanying drawings, in which—

Figure 1 is a front elevation of the machine, partly broken away. Fig. 2 is a side elevation, partly broken away. Fig. 3 is a section on the line 3-3 of Fig. 1. Fig. 4 is an end

view of the carriage and platen-frame, showing the line-spacing mechanism. Fig. 5 is a top plan view of the magnets which control the inking-rollers. Fig. 6 is a detailed view showing the manner of securing the platens to the shafts. Fig. 7 is a section on the line 7-7 of Fig. 3, showing the arrangement of the type-wheel magnets; and Fig. 8 is a diagram illustrating the circuits of the various magnets and the operation of the type-wheel magnets.

In the drawings, 1 indicates the frame of the machine, on the upper part of which is arranged a carriage 2, movable longitudinally upon rollers 3, which travel in guideways 4. The carriage is provided upon its under surface with a toothed rack 5. A spacing-pawl 6, actuated by an electromagnet 7, is adapted to draw the carriage one space to the left upon the depression of a key against the action of a spring 8 upon the right-hand end of the machine. Obviously a weight or other form of motor may be substituted for the spring 8. A suitable spring holding-pawl 9 engages the rack for the purpose of retaining the carriage in the position to which it is drawn by the spacing-pawl. The holding-pawl 9 is connected to an armature 10 of an electromagnet 11. When it is desired to return the carriage to the right-hand end of the machine, the holding-pawl 9 is disengaged from the rack by the depression of a key provided for the purpose, which closes the circuit through the magnet 11, and the latter draws downward the armature and pawl 9. The spring 8 then draws the carriage back.

Supported upon the carriage is a platen-carrying frame consisting of a base 12, movable in transverse guides 13, and an upright frame 14, rigidly secured thereto, the latter having journaled in its ends 15 a vertical series of horizontal shafts 16, upon each of which is arranged a series of platens 17. The platen-frame moves longitudinally on the machine with the carriage, and it is given a transverse reciprocating movement upon the carriage by means of the springs 18 and a pair of bell-crank levers 19, connected to the armatures 20 of electromagnets 21, located near the ends of the machine, said magnets being energized upon the depression of the various character-keys on the keyboard as

will be hereinafter described. The upper ends of the levers 19 extend into a longitudinal channel 21^a in the platen-frame, so that the frame may move freely longitudinally, and the engagement of the levers with the sides of the channel will give said frame the necessary transverse movement. To give rigidity to the shafts 16, uprights 22, having bearings through which the shafts pass, are arranged on the platen-frame between the vertical rows of platens.

The platens 17 are secured upon the shafts 16 by means of threaded clamping-nuts 23, arranged at one end of each platen and adapted to force the platen against a stop 24, fixed to the shaft at the opposite end of the platen. When the nuts 23 are tightened, the platens on each shaft rotate together; but by unscrewing the nut 23 any platen may be turned independently of the others, as is necessary in placing or removing the paper.

The several shafts carrying the platens are arranged to move in unison by means of ratchet-wheels 25, Fig. 4, secured to the shafts 25 and operated by pawls 26, carried by arms 27, journaled upon the shafts, the arms being connected together by means of a rod 28. Rigidly connected with one of the arms 27 is an armature 29, controlled by an electromagnet 30 in circuit with a line-spacing key on the keyboard. It will be seen that upon closing the circuit of the magnet 30 the latter will attract its armature 29, and thereby rotate the platens upon each of the shafts. When the circuit is interrupted, a spring 31 returns the pawls 26 to their normal position. Suitable means may also be employed to regulate the line-spacing by arranging the pawl to engage every tooth or every second tooth or every third tooth, as is common in type-writing machines. As shown in the drawings, this is accomplished by an adjusting-screw 32, by means of which the range of movement of the armature 29 is regulated.

In front of the carriage is arranged a series of vertical shafts 33, one for each vertical row of platens, each shaft carrying as many type-wheels 34 as there are horizontal rows of platens on the carriage. As shown in the drawings, there are three type-wheel shafts, each carrying two type-wheels. The shafts 33 are movable vertically and their lower extremities are journaled in a horizontal bar 38, supported by the shafts, and by means of which the several shafts and the type-wheels carried thereby may be elevated or lowered in unison. The type-wheels 34 are splined to the shafts, the wheels upon each of the shafts being separated by sleeves 39 of uniform length. The shafts 33 and type-wheels are made as light as possible, and a spring 40 may be placed on each shaft to insure the quick return of the type-wheels and steady the movement. Each type-wheel is provided with a set of lower-case type 41 at the top, upper-case type 42 in the center, and figures and odd characters 43 at its lower end. The

lower-case letters are thus normally opposite the impression-point on the platen. The bar 38 is raised by means of levers 44 and 45, operated by their respective electromagnets 46 and 47, the circuits of which are controlled by two keys upon the keyboard. The levers 44 are arranged to move the type-wheel shafts, so that the upper-case letters 42 will be opposite the impression-point, and the levers 45, which are longer, are arranged to elevate the shafts, so that the odd characters 43 will come opposite the impression-point. The several shafts 33 may also be rocked in either direction by means of a horizontal rack-bar 48, which engages pinions 49, secured to each of the shafts below the type-wheels. The pinions 49 are elongated, so that their teeth will engage the rack throughout the entire vertical movement of the shafts 33. The type which are used most frequently are located near the rear of the type-wheels, and those which are used infrequently are arranged upon the sides and toward the front of the wheels in the inverse order of their usefulness with reference to the platens.

The rocking of the type-wheel shafts is effected by means of an arm 50, the upper end of which engages the rack-bar 48, while its lower end is rigidly connected to an arc-shaped iron armature 51, which armature is centrally mounted on a pivot 52. It will readily be seen that a movement of the armature 51 about its pivotal point in either direction will impart to the type-wheels, through the intermediate connections, a corresponding movement, and by moving the armature a proper distance any desired type upon the several type-wheels may be brought opposite the printing-points on their respective platens, while a simultaneous upward movement of the bar 38 will bring the upper-case letters or odd characters into position when desired. A forward movement of the platen-frame will then bring the platens against the type-wheels and imprint the characters, the type having been inked during the rotation of the wheels, as will be hereinafter explained.

The armature 51 is controlled by electromagnets 53 and 54, Figs. 7 and 8, carried by arms or levers 55 and 56, respectively, which are free to swing on a common pivot 57, secured to the frame of the machine centrally of the keyboard. These magnets 53 and 54 I shall for convenience call "type-wheel" magnets. The levers 55 and 56 normally rest upon the inner ends of the key-levers 65, Fig. 3, and the fulcrum 66 of the latter are so arranged that the keys on the right and left halves of the keyboard will, when depressed, raise the magnet-levers 56 and 55, respectively, the amount of movement imparted to said magnet-levers being determined by the position of the fulcrum-point 66 of the key-lever operated and its proximity to the central line of the keyboard.

It will be noted that the extent of movement of the arm 50 about its axis, and there-

fore of the type-wheels 34, will depend upon the position of the type-wheel magnets 53 and 54, as the case may be, when energized. If the magnet 53, for instance, is raised to a point near the center of the arc and then energized, the attraction of the armature will cause a greater movement of the arm 50 and the type-wheels than when the magnet is nearer a horizontal position when energized.

10 The action of the magnet 54 will of course be similar, but will impart an opposite movement to the type-wheels. The circuits of the magnets 53 and 54 are normally open; but when either magnet has been moved into position by the depression of a key the circuit through the magnet is then closed by means of a circuit-closer located beneath and operated by the key-lever. The closing of the circuit results in the attraction of the armature 51 and the consequent rotation of the type-wheels until the type corresponding to the key depressed are brought to the printing-point. The arm 50 and armature 51 are normally maintained in a central position by means of suitable springs 67.

In order that the type-wheel magnets 53 and 54 may be correctly positioned with reference to the armature upon the depression of any given key, I provide a semicircular rack 68, 30 extending parallel with and adjacent to the armature 51, the teeth 69 upon both sides of the rack sloping upwardly, and I arrange upon the ends of the levers 55 and 56 spring-pressed pins 70, which slide freely over the 35 inclined teeth of the rack during the upward movement of the lever, but are prevented from returning by the formation of the teeth. When one of the levers 55, for instance, is raised into position by the depression of a 40 key, the pin 70 passes freely over the rack until the upward movement of the lever is complete, when it is pressed into a notch in the rack by means of a spring 71, and the lever and magnet are held in position until the 45 armature is attracted to the poles of the magnet. The pins 70 are movable longitudinally of the levers 55 and 56 in slots 72, but are normally held in their outermost position in engagement with the rack by suitable springs 50 73, connected to a rod 74, through which the pin passes. When the armature is attracted by a magnet, it engages a projection on the rod 74, and the pin is thereby drawn inwardly and becomes disengaged from the rack. The 55 spring 71 then depresses the pin, so that its outer end will extend below and alongside of the rack, and the lever and magnet will drop to their normal position when the key is released and the magnet deenergized, the pin 60 sliding down in contact with the inner side of the rack-frame. The lower ends 75 of the rack-frame are inclined, as shown, and when the pin reaches its lowermost point the spring 73 draws it outward onto the inclined surface 65 75, from which position it will pass on to the rack, when the magnet-lever is again raised.

The type upon the right side of the type-

wheels are inked by means of inking-rollers 78, Figs. 1 and 5, carried by arms 79, which are secured to rock-shafts 80, and the type 70 upon the left side of the type-wheels are inked by means of inking-rollers 81, secured in a similar manner to rock-shafts 82. The shafts 80 are mechanically coupled by means of a rod 83, connected to arms 84 upon the shafts, 75 whereby they are all rocked together. In like manner the shafts 82 are connected by means of a rod 85, connected to arms 86 upon the shafts. The shafts 80 are rocked through the medium of an electromagnet 87, acting 80 upon an armature 88, which is rigidly connected to one of the shafts. The attraction of the armature, as will readily be seen, will force the inking-rollers 78 against the type-wheels, and the retraction of the armature 85 by a spring 89 will withdraw the rollers from the type-wheels. Similarly the rollers 81 are operated by means of an electromagnet 90, armature 91, and spring 92.

The current for the various circuits may be 90 derived from any convenient source, such as the battery 95, Fig. 8. One pole of this battery is connected by a wire 96 to a contact-plate 97, insulated from the frame of the machine and common to all of the circuit-closers 95 of the keyboard. The circuit-closers, as shown, consist of pins 98, which are supported in and extend through a series of metal plates 99, insulated from the frame and from each other and supported above the plates 97, each 10 pin having interposed between its head and the plate a compression-spring 100, which forces the pin against the lower side of the key-lever 65. The circuit-closers corresponding to the character-keys upon the left-hand side of the keyboard are mounted in a plate 100, and the circuit-closers corresponding to the character-keys upon the right-hand side of the keyboard are mounted in a plate 102. The circuit-closers which operate the magnets 11, 110 46, 47, and 30 are mounted in independent plates or blocks 103, 104, 105, and 106, connected to independent circuits, so that the operations performed by any one of these magnets may be accomplished singly. The 115 several circuits of the machine may, as shown, be connected to a common return-wire 107. The circuit of the magnet 53 extends from the plate 101 via wire 108 to the magnet, and thence via wire 109 to the common return-wire 107, and the circuit of the magnet 54 extends from the plate 102 via wire 110 to said magnet, and thence via wire 111 to the common return-wire 107. These circuits are normally open at a switch 63, located beneath 125 the pivotal point of the magnet-levers 55 and 56. This switch consists of a pair of concentric arc-shaped contact-pieces 112 and 113, located in the circuit of the magnet 53 to the left of a central line through the pivot 45, and a similar pair of plates 114 and 115, located upon the right of said central line in the circuit of magnet 54. Connected to the pivotal 130 end of the lever 55 and extending downwardly

at right angles thereto is a narrow metallic switch-rod 116, which serves to electrically connect the contact-plates 112 and 113 when the lever 55 is elevated, but which normally is out of contact therewith when said lever is in the horizontal position. A switch-rod 117 is similarly mounted upon the lever 56 and is adapted to electrically connect the contact-pieces 114 and 115 when the lever 56 is elevated and to break the connection when said lever is in the horizontal position. The spacing-magnet 7 is connected to each of the plates 101 and 102 via wires 108 and 110 and to the common return-wire 107 by wire 118. In like manner the circuit of the left-hand inking-magnet 90 extends from the plate 101 to the wire 107 via wires 108 and 119, and the circuit of the right-hand inking-magnet 87 extends from the plate 102 to the wire 107 via wires 110 and 120.

It will be seen that when the levers 55 and 56 are in their horizontal position the circuits through magnets 53 and 54 will be interrupted at the switch 63. When, however, a key upon the left-hand side of the keyboard is depressed, the lever 55 will be raised and the rod 116 will connect the contact-pieces 112 and 113. When the key has been fully depressed, the current will flow from the battery by way of wire 96 and plate 97 through the circuit-closer operated by the key, thence through plate 101, wire 108, contact-pieces 112 and 113 and rod 116 to magnet 53, returning through wires 109 and 107 to the battery. At the same time current will pass to the spacing-magnet 7 through wires 108 and 118 and to the left-hand inking-magnet 90 through wires 108 and 119. Each of these magnets 53, 7, and 90 will therefore be energized at the same time. The spacing-magnet 7 will attract its armature, and thereby draw the carriage forward one notch, and the inking-magnet 90 will attract its armature and force the left-hand inking-rollers 81 against the type-wheels. The magnet 53 will attract the armature 51, thereby effecting a rotary movement of the type-wheels to the left, bringing the proper type opposite the impression-point, as before described, the type being inked by contact with the roller during rotation. The next movement required is the forward movement of the platens, which is accomplished by the magnets 21. In order to effect this movement at the proper time, I arrange upon the faces of each of the levers 55 and 56 and near their extremities two contact-points 121 and 122. The two contact-points 121 are connected to one terminal of the magnet 21 by means of a wire 123, and the other terminal of the magnet is connected to wire 107. The contact-point 122 upon the lever 55 is connected to the circuit 108 above the switch 63, and the contact-point 122 upon the lever 56 is similarly connected to the wire 110. Connected to the outer extremities of each of the rods 74 I arrange an insulated rolling contact device 124, which is adapted to move back and

forth with said rod and to roll across the contact-points 121 and 122 just before the pin 70 drops out of the rack—in other words, just before the movement of the armature toward the magnet is completed. The circuit of the magnet 21 is thus made and broken by the inward movement of the rolling contact, and the roller is prevented by the pin 70 from passing back over the contacts until the lever drops to the horizontal position. It will therefore be seen that the platen-frame will be given a forward movement by the magnet 21 at about the time when the type-wheels have reached their intended position, and, by proper adjustment the platens may be made to strike the type at about the instant the latter have ceased to move.

The key is held down during the above cycle of movements; but when it is released the circuit is broken at the keyboard and the lever 55 drops to the horizontal position. When the lever 55 drops to the horizontal position, the rod 116 leaves the contact-points 112 and 113, and the circuit through the magnet 53 is interrupted at these points, so that no current can pass through this magnet until a left-hand character-key is again depressed. If a character-key upon the right-hand side of the board be now depressed, the lever 56 will be raised and the switch-rod 117 will connect the points 114 and 115, and upon the completion of the circuit at the keyboard the magnet 54 will become energized and simultaneously the current will flow through the right-hand inking-magnet 87 by way of the wires 110 and 120 and through the spacing-magnet by wires 110 and 118. The armature 51 upon being attracted by the magnet 54 effects a movement of the type-wheels to the right. It also draws inward the pin 70 and the roller contact device 124 upon the lever 56, and the current will then flow via the wire 110, contacts 114 115, roller-contact 124, and wire 123 to the magnet 21, thus effecting the same order of movements.

When the space-key 62 is depressed, as neither of the magnet-levers are raised no current will pass through the type-wheel magnets or the platen-moving magnets 21, but current will pass through the spacing-magnet 7 via circuit-closer 64 and wires 110 and 118, and the carriage will thereby be moved forward. When it is desired to print upper-case letters, the key corresponding to circuit-closer 104 is depressed simultaneously with the depression of the character-key, and to print odd characters the key corresponding to circuit-closer 105 is depressed at the same time as the character-key. In order to release the carriage and allow it to be drawn back by the spring 8, the key corresponding to circuit-closer 103 is depressed, and in order to rotate the platen-cylinders the key corresponding to circuit-closer 106 is depressed, the various magnets connecting with these keys being energized independently, as will readily be seen by an inspection of the circuits, and the

movements effected by them being as hereinbefore described.

The operation of my improved type-writer will be understood from the foregoing description.

What I claim, and desire to secure by Letters Patent, is—

1. A type-writer comprising a plurality of platens arranged upon separate shafts, a common carriage upon which said shafts are mounted, means for imparting a step-by-step movement to the carriage to effect letter-spacing and connections between the platens constructed to rotate them to effect simultaneous line-spacing, substantially as described.

2. A type-writer comprising a plurality of platens, connections between the platens for rotating them to effect simultaneous line-spacing, and means for disconnecting individual platens whereby they may be rotated independently if desired, substantially as described.

3. A type-writer comprising a carriage, means for imparting a step-by-step movement to said carriage to effect letter-spacing, a platen-frame movable laterally upon the carriage to effect printing, a plurality of platens supported upon said frame, and a corresponding plurality of sets of type, substantially as described.

4. A type-writer comprising a plurality of platens suitably connected to effect simultaneous line and letter spacing, in combination with a corresponding plurality of type-wheels, each carrying a set of type, and connections between said type-wheels whereby like type of each wheel may be simultaneously brought to the impression-point, substantially as described.

5. In a type-writer, the combination with a platen and a type-wheel shaft carrying a type-wheel, of means for rocking said shaft to bring the selected type in front of the platen, consisting of an armature mechanically connected to said shaft, a magnet movable along said armature and keys for effecting the movement of the magnet, and means for impressing the selected type against the platen, substantially as described.

6. A type-writer comprising a plurality of platens suitably connected to effect simultaneous line and letter spacing, in combination with a corresponding plurality of type-wheels, and means for rotating said type-wheels simultaneously and simultaneously impressing the selected type upon the platen, substantially as described.

7. A type-writer comprising a plurality of platens, in combination with a corresponding plurality of type-wheels, means for simultaneously rotating said type-wheels and means for simultaneously adjusting said wheels longitudinally whereby given type may be simultaneously brought to the printing-points of said type-wheels, substantially as described.

8. In a type-writer, the combination with

a plurality of type-wheelshafts carrying type-wheels arranged to move in unison, and a corresponding number of platens adjacent to said type-wheels and movable in unison, of means for imparting to said shafts a rotary movement, and means for imparting to said platens a reciprocating movement toward and from said type-wheels, substantially as described.

9. In a type-writer, the combination with a type-wheel shaft, of means for rocking said shaft consisting of an armature mechanically connected to said shaft, a magnet movable along said armature, and keys for effecting the movement of the magnet, substantially as described.

10. In a type-writer, the combination with a plurality of type-wheel shafts, of means for rocking said shafts in unison consisting of an armature mechanically connected to said shafts, a magnet movable along said armature, and keys for effecting the movement of the magnet, substantially as described.

11. In a type-writer, the combination with a plurality of type-wheel shafts, of means for rocking said shafts in unison consisting of an armature mechanically connected to each of said shafts, an electromagnet movable along and adjacent to said armature, and keys for moving said magnet and closing the circuit thereof, substantially as described.

12. In a type-writer, the combination with a plurality of type-wheel shafts carrying type-wheels, of means for rocking said shafts in unison consisting of a pivoted armature mechanically connected to said shafts and a magnet movable along said armature toward and from its pivotal point, and keys for effecting such movement, substantially as described.

13. In a type-writer, the combination with a plurality of type-wheel shafts carrying type-wheels, of means for rocking said shafts in unison in either direction, consisting of pinions mounted on each of said shafts, a rack engaging said pinions, an armature in engagement with said rack, and a movable magnet adjacent to said armature, substantially as described.

14. In a type-writer, the combination with a plurality of type-wheels, of a pivoted armature and one or more magnets movable toward and from the pivotal point of said armature, and connections between said armature and type-wheels whereby the latter will rotate in unison when the armature is moved, substantially as described.

15. In a type-writer, the combination with a plurality of type-wheels arranged to move in unison, of an arc-shaped armature centrally pivoted and connected to said type-wheels, and a magnet movable along said armature, substantially as described.

16. In a type-writer, the combination with a plurality of type-wheels arranged to move in unison, of an arc-shaped armature pivoted at its middle point and connected to said type-

wheels, and a magnet pivotally mounted at the center of the arc formed by the armature, substantially as described.

17. In a type-writer, the combination with 5 a plurality of type-wheels arranged to move in unison, of an arc-shaped armature pivoted at its middle point and engaging said type-wheels through intermediate connections, a pair of magnets radially mounted upon a 10 pivot at the center of said armature and key-levers for moving said magnets, independently, substantially as described.

18. In a type-writer, the combination with 15 a plurality of type-wheels arranged to move in unison, of an arc-shaped armature pivoted at its middle point and engaging said type-wheels through intermediate connection, an arc-shaped rack adjacent to said armature, a pair of magnets mounted upon levers pivoted 20 at the center of said armature and rack, a spring-pressed pin upon the end of each of said levers for engaging the rack when a lever is raised from its normal position and means for drawing said pin from the rack 25 when the armature is attracted by the said magnets upon said lever, substantially as described.

19. In a type-writer, the combination with 30 a carriage having a rack, and a motor for impelling the carriage toward the right, of a spacing-pawl adapted to engage the rack and an electromagnet controlled by the space-key and character-keys for operating said pawl to move the carriage to the left against the 35 action of said motor, a holding-pawl normally engaging the rack, and an electromagnet controlled by an independent key for disengaging said holding-pawl from the rack, substantially as described.

20. In a type-writer, a plurality of platens 40 mounted upon separate shafts, and means for rotating said shafts in unison to effect line-spacing consisting of ratchet-wheels secured to each of said shafts, pawls in engagement with said ratchet-wheels, each of said pawls 45 being mounted upon a rocking arm, a connecting-rod between said arms, an armature secured to one of said arms, and an electromagnet controlled by an independent key, adjacent to said armature, substantially as 50 described.

21. In a type-writer, the combination with a type-wheel, and means controlled by the keyboard for rocking the same in either direction from its normal position, of a pair of 55 inking-pads, one arranged on each side of the type-wheel, electromagnets for impressing said pads against the type-wheels, and means for energizing one of said magnets when the wheel is rocked in one direction and for energizing the other magnet when the wheel is rocked in the opposite direction, substantially as described.

22. In a type-writer, the combination with a plurality of type-wheels, and means controlled by the keyboard for rocking the same 60 in unison, of an inking-pad adjacent to each of said wheels, mechanical connections between said pads, and electromagnetic means for impressing said pads against said wheels 65 when the latter are rocked, substantially as described.

In testimony whereof I affix my signature in presence of two witnesses.

WILLIAM T. HOOFNAGLE.
